Specification for Design.

Patented Feb. 19, 1918.

Application filed November 25, 1916. Serial No. 133,501. Term of patent 7 years.

To all whom it may concern:

Be it known that I, JOSEPH W. JONES, a citizen of the United States, and resident of the borough of Manhattan, in the city and State of New York, have invented a new, original, and ornamental Design for a Tire, of which the following is a specification, reference being had to the accompanying drawing, forming part thereof.

My new design for a tire is shown in the accompanying drawing, in which—

Figure 1 is a perspective view of the tire, and

Fig. 2 is a plan view of a portion of the tire on a larger scale.

I claim:

The ornamental design for a tire, as shown.
JOSEPH W. JONES.
